(57) **CLAIM**

The ornamental design for a packaging container for electronic goods, as shown and described.

DESCRIPTION

FIG. 1 is a perspective view of a packaging container for electronic goods according to our new design;

FIG. 2 is a front elevational view thereof;

FIG. 3 is a left side elevational view thereof;

FIG. 4 is a top plan view thereof;

FIG. 5 is a bottom plan view thereof;

FIG. 6 is a perspective view thereof, with the broken line showing a camcorder placed in the packaging container for electronic goods, being for illustrative purposes only and forming no part of the claimed design;

FIG. 7 is a sectional view taken along the line 7—7 of FIG. 2; and,

FIG. 8 is a sectional view taken along the line 8—8 of FIG. 4. The structure shown in broken line represents unclaimed portions of the design and forms no part of the claimed design.

The broken lines in the drawings are for illustrative Purpose only and form no part of the claimed design.
